Primary Examiner — Mark Goodwin(74) *Attorney, Agent, or Firm* — The Maxham Firm(57) **CLAIM**

The ornamental design for a control panel for machine tools, as shown and described.

DESCRIPTION

FIG. 1 is a perspective view of the control panel for machine tools according to the invention, showing peripheral elements added;

FIG. 2 is a front view thereof; the wavy line shown at the bottom of the FIGS. 2-9 being indicative of indeterminate length;

FIG. 3 is a right side view thereof;

FIG. 4 is a front view of the control panel for machine tools, minus the peripheral elements of FIG. 1;

FIG. 5 is a back view thereof;

FIG. 6 is a a is an enlarged front view thereof, with the control panel rotated downward with respect to the view panel;

FIG. 7 is a right side view of the invention in the orientation of FIG. 4;

FIG. 8 is a right side view of the FIG. 7 orientation with controls and indicators stripped off; and,

FIG. 9 is a right side view of the invention in the orientation of FIG. 6.

The broken line showing of various surface features and attachments is included for the purpose of illustrating elements of the control panel for machine tools and forms no part of the claimed design.
